UNITED STATES PATENT OFFICE.

WILLIAM A. MARKEY, OF MOUNDSVILLE, WEST VIRGINIA.

DOOR-LOCK.

No. 878,972.

Specification of Letters Patent.

Patented Feb. 11, 1908.

Application filed February 9, 1907. Serial No. 356,574.

To all whom it may concern:

Be it known that I, WILLIAM A. MARKEY, a citizen of the United States of America, and resident of Moundsville, county of Marshall, and State of West Virginia, have invented certain new and useful Improvements in Door-Locks, of which the following is a specification.

This invention relates to new and useful improvements in door-locks, and it has for its object to provide a simple, durable and comparatively inexpensive lock for doors which requires that only a small mortise be cut in a door for its accommodation.

15 A further object is to provide a lock for doors in which a simple lever is employed for the operation of the door-bolt, thus dispensing with the ordinary door-knob which requires a turn of the wrist to operate said bolt.

20 With these and other objects in view, the invention finally consists in the particular construction, arrangement and combination of parts which will hereinafter be fully described, reference being herein had to the 25 accompanying drawings, forming a part of this specification, in which—

Figure 1 is a side elevation of the lock applied to a door; Fig. 2 is a longitudinal vertical section of the lock, taken just inside the 30 face-plate thereof; Fig. 3 is a top plan view of the invention; Fig. 4 is a cross section on the line 4—4, Fig. 1; Fig. 5 is a similar section on the line 5—5, Fig. 1; Fig. 6 is a perspective view of the bolt; Fig. 7 is a front 35 elevation of the locking slide; Fig. 8 is a perspective view of the key-operated locking-plate; and—Fig. 9 is a detail view of the key employed.

Referring to said drawings, in which like 40 designating characters denote like parts throughout the several views—1 indicates a door in which is cut a mortise 2 of a size slightly greater than is sufficient to accommodate the working parts of the lock. Fitted 45 within said mortise with the face-plates 3 thereof in close embracing engagement with the faces of the door on opposite sides are the main working parts of the lock. The parallel face-plates 3 are formed integral, having 50 a connecting plate 4 across the front end which effectually closes the end of the mortise 2. A vertical cross-plate 5, which is also preferably formed integral with the face-plates 3, but which may be attached separately, stands at a suitable distance in the rear 55 of the connecting-plate 4. A suitable open-

ing 6 is provided in the connecting-plate 4 in which is held the enlarged front end, or head, 7 of a movable lock-bolt 8 which consists of a yoke 9, a cylindrical stem 10 having 60 its rear end rigidly mounted in the front end of said yoke, and said head 7, which latter is integral with said stem.

The stem 10 is projected through and is movable in a central opening or aperture 11 65 provided in said cross-plate 3, and has its rear end mounted in the head 12 of the yoke 9, as hereinbefore mentioned. A pin 13 projected through said head 12 and said stem 10 connects said parts rigidly together. The 70 yoke consists of said head 12 and two parallel yoke-members 14 which are integral therewith, one of said members directly overlying the other.

Mounted one over the other upon a vertical pivot-pin 15 carried by the rear end of the yoke 9 are the flattened ends 16 of oppositely-disposed hasps 17 which project transversely outward through slots 18 provided in the face-plates 3. The bodies of 80 said hasps on the outer sides of said face-plates are bent laterally and extend rearwardly substantially parallel to said face-plates, bearing upon their ends suitable knobs 19. Projecting flanges 20 are preferably provided on said face-plates 3 at the edges of said slots 18, the adjacent faces of said flanges being plain and flat and constituting bearing 85 surfaces for the movable hasps.

Extending transversely between the members 14 of the yoke 9, and having its ends revolvably mounted in the face-plates 3, is a pin or spindle 21; and fitted upon said spindle between the inner face-plate 3 and the yoke is a sleeve 22, the object of which is to 90 firmly hold said yoke at a distance from said inner face-plate substantially in line with the openings 11 and 6. Pivotally mounted upon said spindle 21 on the opposite side of the yoke is a locking-plate 23, and a coil-spring 100 24 encircling the spindle has one end seated against said locking-plate and its other end against the inner face of the outer face-plate, as shown. Said locking-plate consists of a longitudinal flat body 25 of greater width 105 than the space between the yoke-members 14 and of a length slightly less than the distance between the head 12 of the yoke and the broadened lug-like ends 26 of the yoke-members. The ends of the plate 25 are 110 rounded for a purpose which will hereinafter be made apparent, and integral inwardly

projected lugs 27 having rounded points are carried by said plate, as shown. In the outer face of the body 25 on opposite sides of its central opening are sockets 28 for receiving the prongs 29 of a key 30 which is adapted to be inserted thereto from the outer side of the lock, a longitudinal slot 31 being provided in the outer end of the spindle for admitting the key. Recesses 32 are provided in the outer 10 face-plate 3 for admitting the end 33 of the key therethrough, the spindle being first turned to cause its slot 31 to register with said recesses. Recesses 34 suitably located in the key admit of its turning in the opening 15 of the face-plate when it has been inserted to the proper depth for engagement with the locking-plate 23.

The locking-plate 23 normally stands vertical as shown in Figs. 1 and 2, thus admitting 20 of a free longitudinal movement of the lock-bolt 8. An outward pull on the knob 19 throws the lever-like hasp 17 forward against the face-plate 3 at the front end of the slot 18, which serves as a fulcrum, and, turning 25 on the pivot-pin 15, withdraws said bolt 8 against the tension of the spring 35 which encircles the stem 10 between the bolt-head 7 and the cross-plate 5. Upon releasing the knob 19, said spring 35 again throws the bolt 30 outward.

To lock the bolt 8 against movement, the key 30 is inserted as hereinbefore described until its prongs 29 engage the sockets 28 of the locking-plate 23; then, turning said key, the said locking-plate is revolved on the spindle 21. When the lugs 27 engage the beveled edges of the yoke-members 14, the locking-plate is gradually forced outward against the tension of the spring 24, allowing the lugs to 35 pass over said members and to drop therebetween, as shown in Figs. 3 and 5, in which figures the said locking-plate is shown longitudinally against the yoke with its lugs between the members thereof and its front end 40 adjacent to the head 12 thereof, thus preventing longitudinal movement in said bolt 8.

A locking-slide 36 is also provided by means of which the bolt 8 may be locked against movement from the inner side of the door. Said slide is fitted in a channel 37 provided therefor in the face of the cross-plate 5 and carries an extension 38 which projects outward through the inner face-plate 3 and is bent to form a finger-piece 39. 55 Said slide has a circular hole or aperture 40

through which, when it registers with the hole 11 in the cross-plate 5, the stem 10 freely moves. Also provided in said slide is a slot 41 of less width than the diameter of said hole 40, which slot communicates at one 60 end with said hole. In the upper and under sides of the rear end of the stem 10 are provided recesses 42, as shown, into which the edges of the slide on the opposite sides of the slot 41 are adapted to be drawn, thus locking 65 the bolt against longitudinal movement.

Having thus described my invention, what I claim as new, and desire to secure by Letters Patent, is—

1. In a door-lock, face-plates, a movable 70 bolt interposed between said plates, means for normally holding said bolt forced outward, a yoke carried by said bolt, a key-operated locking-plate having inturned ends adapted for interlocking with said yoke 75 when in one position, means for normally holding said locking-plate in engagement with said yoke, said locking-plate being adapted for locking said bolt against retraction when the former occupies one position 80 and for admitting of free movement of the bolt when it occupies another position.

2. In a door-lock, face-plates and a connecting end-plate, a movable bolt comprising a head, a stem and a yoke, said bolt 85 interposed between said plates, means for normally holding said bolt forced outward with respect to said plates, a revoluble spindle extending transversely between the members of said yoke and having its ends 90 mounted in said face-plates; said spindle being slotted at one end for the reception of a key, a locking-plate having inturned ends revoluble upon said spindle, a spring interposed between said locking-plate and one of 95 said face-plates for holding the former against the yoke-members, levers pivotally attached to the rear end of said yoke and projecting outward through said face-plates, and means whereby the retraction of said 100 bolt is prevented when the inturned ends of the locking-plate stand between the yoke-members.

Signed by me in presence of two subscribing witnesses.

WILLIAM A. MARKEY.
